UNITED STATES PATENT OFFICE

HANS KARL KLOESS, OF HAMBURG, GERMANY

SHIP BUILDING

Application filed September 10, 1927, Serial No. 218,679, and in Germany May 21, 1927.

My invention relates to ships, and its particular object is the designing of vessels so as to determine the most favorable contour lines of the hull of such vessels below the water-line. In accordance with the present invention the general direction of the frames which may either be straight or curved, and their different inclinations relative to the horizontal are determined by generating lines radiating from a point located below the plane of the bottom of the ship. This point need not have the same position with relation to the central plane of symmetry for the fore and aft sections of the vessel, since these points may occupy a different relative position so as to give a different degree of inclination to the frames in the fore and aft sections of the vessel.

On the accompanying drawing I have illustrated the principle of my invention.

In the single figure of the drawing, the line W—A—Z denotes the water-line of the ship, while the line X—Y denotes the central symmetrical plane in the longitudinal direction of the vessel. B is the bottom line of the vessel, while A, A' indicate the side walls which as shown in the drawing downwardly extended by the broken lines form with line B and line W—A—Z a rectangle. The lines O—A and Oa—A represent the main diagonal of the vessel.

From the point O¹ outside of the hull and disposed below the bottom line B radiating lines 1¹, 2¹, 3¹, 4¹, 5¹, 6¹ are generated which lines determine the direction of the frames of the fore section, while from another point O² disposed outside the hull below the bottom line B radiating lines 1, 2, 3, 4, 5, 6 are generated which determine the direction of the frames of the aft-section of the ship.

Point O¹, the radiating lines from which point determine the degree of inclination of the frames in the fore-part of the vessel is located at a comparatively large distance from the bottom line B of the vessel, the location depending on the ratio of the beam W—Z to the depth W—O and also the speed for which the vessel is built.

Point O², the radiating lines from which point determine the degree of inclination of

the frames in the aft part of the vessel is located closer to the bottom-line B, and the location of this point likewise depends on the ratio of the beam of the vessel to its depth and the speed.

As clearly shown on the drawing, the frames in the fore part of the vessel, on the right hand side, have a steeper inclination therefore including a larger angle with the bottom line B than the frames in the aft part of the vessel, on the left hand side, which include a smaller angle with the bottom line B.

At the junctions of the frames with the bottom and side walls of the vessel, they are rounded off, as indicated by the small curved broken lines.

By my method as above described, I am enabled to produce standard designs for the hulls of sea-going vessels resulting in the most favorable contour lines below the water-line for the smooth and rapid backward flow of the water when the vessel is in motion along the shortest path, whereby eddies are avoided and friction is reduced to a minimum.

It should be understood that the invention has been herein shown and described in its broad features only, and that it is not dependent upon the particular position of the centers of intersection of the ribs, nor on the configuration of said ribs and the relative position thereof, and that modifications are possible, except as otherwise stated in the appended claims.

To locate the points O¹, O² for any particular vessel involves a variety of considerations and while no mathematical calculations have as yet been devised for accurately locating these points, same may be substantially accurately located on the known basis that for a given speed, the greater the depth and beam of the vessel the nearer said points must be located to the line A—Y and farther from the bottom B, these distances being respectively increased and decreased to enable increased speed of the vessel. As a general proposition, it may be stated that for medium speed, medium draft vessels the point O¹ may be located below the bottom B a distance approximating the beam of the vessel, and outwardly from the center line X—Y a distance ap-

proximating the depth of the vessel, while the point O^2 may be located below the bottom B and outwardly of the center line X-Y substantially equal distances approximating the draft or one half the beam of the vessel. The approximate proper locations of the points O^1 , O^2 thus being known for a vessel of medium speed and medium draft, it is possible, on the known basis that increasing the beam and draft of the vessel necessitates shifting of said points as aforesaid, to approximate the proper location of said points for a vessel of any particular beam, draft and speed. Or, of course, substantially accurate positioning of said points may be determined by experimentation.

I claim:-

1. The method of determining the inclination of the frames in the fore and aft section of a ship which consists in generating from a point below the bottom line of the ship radiating lines to points on the main diagonals of the vessel, the location of said point depending on the ratio of the beam of the ship to its depth measured from the water-line.
2. The method of determining the inclination of the frames in the fore and aft section of a ship, which consists in generating from two differently located points below the bottom line of the ship radiating lines to points on the main diagonals of the vessel, the location of said points depending on the ratio of the beam of the ship to its depth measured from the water-line, the point for determining the inclination of the frames in the aft section being located closer to the bottom line than the point for determining the inclination of the frames in the fore-section.

In testimony whereof I have affixed my signature.

HANS KARL KLOESS.
